UNITED STATES PATENT OFFICE

AUGUST J. KOEPSELL, OF MAYVILLE, WISCONSIN

GRATE

Application filed June 1, 1929. Serial No. 367,718.

This invention relates to improvements in stove grate shaking mechanism and pertains particularly to a device whereby oscillating grate units may be given various degrees of oscillatory movement.

The invention broadly contemplates the provision of a structure formed to receive the projecting polygonal shaped ends of a plurality of oscillatory grate bars. These projecting ends of the bars are engaged by an operating crank having a guide lug thereon. The projecting ends of the grate bars are received in the structure through aligned apertures in a series of spaced plates, each 15 of these apertures having off-set portions, the off-set of one aperture being in alignment with the off-set of the next or other aperture. Stop members extend between the plates and limit the oscillatory movement of the crank 20 by obstructing the movement of the lug carried thereby. By the arrangement of the stop members various degrees of oscillation of the grate bars are permitted by shifting the crank longitudinally of the grate bar to 25 move the lug through the different apertured plates.

The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from the salient features of the invention, as expressed in the appended claims.

40 In the drawing:

Figure 1 is a vertical view in front elevation of the structure embodying the present invention showing the same in position in a furnace, the structure being sectioned upon the line 1—1 of Figure 2.

Figure 2 is a sectional view taken substantially upon the line 2—2 of Figure 1.

Figure 3 is a sectional view taken substantially upon the line 3—3 of Figure 2, showing an operating crank applied to the structure.

Figure 4 is a sectional view taken substantially upon the line 4—4 of Figure 3.

Referring to the drawing wherein like numerals of reference indicate corresponding parts throughout the several views, the numeral 1 indicates generally the lower portion of a furnace casing showing applied thereto the structure embodying this invention which structure is indicated by the numeral 2 and is formed to receive, as herein-after described, the projecting polygonal shaped ends 3 of the furnace oscillating grate members 4.

The structure comprises an elongated casing 5 having the front wall 6, end walls 7 and a removable back wall 8. The end walls 7 and the top and bottom walls 9 are provided with a flange 10 and that portion of the casing lying between the flange and the removable back wall is adapted to extend through a suitable opening formed in the furnace body 1 so as to bring the flange 10 thereagainst to be secured thereto in the manner shown.

The front and back walls 6 and 8 respectively are provided with suitable aligned apertures to receive the polygonal shaped extensions 3 projecting from the forward end of each of the grates 4, the apertures of the forward wall of the device being of materially greater diameter than the extensions 3, as indicated at 11 so as to permit of the extension therethrough of the enlarged socketed end 12 of a shaking or crank handle 13.

As shown in Figure 1 each of the apertures 11 has a lateral recess 14 opening therefrom to permit of the passage of a lug 15 carried upon the forward end of the crank.

Interposed between the front and back

walls 6 and 8 of the casing is a longitudinally extending partition wall 16. This partition wall is provided with apertures 17 of the same size as the apertures 11 to permit of the passage of the socketed end 12 of the shaking handle, it of course being understood that the apertures of this partition have an extension 3 of a grate passing therethrough, these apertures being aligned with the apertures 11 of the front wall. The aperture 17 of the partition plate 16 has, opening from the edge thereof, a recess 18 which is in alignment with the recess 14 of the aperture 11.

The back plate 8 of the casing and the intermediate or partition plate 16 is held in place by suitable bolts 19 which pass through the front wall of the casing in the manner shown, and surrounding the bolts between the front and partition wall and the partition 20 and back wall are spacing sleeves 20 which maintain the partition in the proper position with respect to the front and back walls.

Disposed on opposite sides of the recesses 14 and 18 and between the front plate and partition plate 16 are stop pins 21.

From the foregoing it will be seen that upon inserting the socketed portion 12 of a shaking handle through one of the apertures 11, the lug 15 will pass through the aperture 30 in upright position, and the socketed end of the handle will receive the forward end of the grate member 3. By stopping the inward movement of the handle with the lug 15 between the wall 6 and the partition 16 and 35 rocking the handle, the pins 21 will permit only slight oscillatory movement of the handle and consequently of the grate bar. This operation may be performed for the shaking of the grate where only the cinders 40 are to be gotten rid of.

If the grate is to be dumped, then the lug of the handle is extended through the recess 18 of the aperture 17 in the partition plate to position between the plate 16 and the rear wall 8. The handle may then be oscillated to turn the grate through a half revolution. If desired in order to prevent complete rotation of the grate, stop pin members 22 may be arranged between the partition 50 plate 16 and the rear wall 8 substantially upon the longitudinal center of the structure so that the lug 15 of the handle will strike thereagainst.

Having thus described my invention, what 55 I claim is:—

1. The combination with a grate having oscillatory bars each having an extension for engagement with a shaker handle, of a chambered casing inclosing each grate extension, 60 a shaker handle formed to receive any one of said extensions and having a stop formed thereon, and means within the chambers of the casing for limiting the oscillatory motion of the handle and grate when the handle is 65 in different positions upon the grate exten-

sion through engagement of said stop therewith, said means permitting more motion with the handle in one position than in another position.

2. The combination with a grate having oscillatory bars each having an extension for engagement with a shaker handle, of a casing adapted to position across the front of the grate and having apertured front and rear walls to permit said extensions to project therethrough, a partition in the casing dividing the same into a pair of chambers, a shaker handle formed to extend through an aperture in the casing front wall to receive a grate extension and having a stop thereon, said partition being formed to permit passage of the grate extensions therethrough and also to permit extension of said handle therethrough, and means adapted to be engaged by said stop for limiting the oscillatory motion of the handle in the casing, the handle having greater motion in one chamber than in the other.

3. The combination with a grate having oscillatory bars each having an extension to receive a shaker handle, of a casing adapted to extend across the front of the grate and having apertured front and back walls for the passage therethrough of the grate extensions, a partition within the casing dividing the same into a pair of chambers and having apertures aligning with the first mentioned apertures, said front wall and partition being formed to permit the extension therethrough of said handle, a lug carried by the handle, and stops disposed at opposite sides of said apertures, between the front wall and partition and between the partition and back wall for engagement by said lug to limit the oscillatory motion of the handle.

4. The combination with a grate having oscillatory bars each having an extension to receive a shaker handle, of a casing adapted to extend across the front of the grate and having apertured front and back walls for the passage therethrough of the grate extensions, a partition within the casing dividing the same into a pair of chambers and having apertures aligning with the first mentioned apertures, said front wall and partition being formed to permit the extension therethrough of said handle, a lug carried by the handle, and stops disposed at opposite sides of said apertures, between the front wall and partition and between the partition and back wall for engagement by said lug to limit the oscillatory motion of the handle, said apertures in the front wall and partition each having a lateral recess to permit the passage of the lug.

5. The combination with a grate having oscillatory bars each having an extension for engagement with a shaker handle, of a pair of stops arranged on an arc concentric with the extension and spaced less than 180°.

grees apart, said stops being positioned at one side of the transverse center of the grate extensions, a second pair of stops for and positioned at the opposite side of the trans-
5 verse center of each extension and disposed upon the same arc as the first mentioned stops but spaced more than 180 degrees apart, and a shaker handle adapted for engagement with each extension and having a lug designed to
10 move between the stops of either of said pair for the control of the oscillatory motion of the grate to which the handle is connected.

In testimony whereof I hereunto affix my signature.
